CLAIM

The ornamental design for a sliding gate opener with waterproof housing, as shown and described.

DESCRIPTION

FIG. 1 is a top perspective view of a sliding gate opener with waterproof housing showing my design:

FIG. 2 is a side view thereof, the opposing side being a mirror image thereof;

FIG. 3 is a front elevational view thereof;

FIG. 4 is a back elevational view thereof;

FIG. 5 is a top plan view thereof; and,

FIG. 6 is a bottom plan view thereof.
